UNITED STATES PATENT OFFICE.

HERMAN DANZIGER, OF NEW YORK, N. Y.

INHALER AND NEURALGIC PENCIL.

Application filed March 26, 1923. Serial No. 627,557.

To all whom it may concern:

Be it known that I, HERMAN DANZIGER, citizen of the Republic of Russia, residing at New York city, New York, have invented 5 new and useful Improvements in Inhalers and Neuralgic Pencils; of which the following is a specification.

My invention relates to an improved construction for a combined inhaler and neuralgic pencil, and has for its object to provide an article of this character which is simple in construction, hygienic and efficient in operation, and which comprises a series of interchangeable, nested compartments designed 15 to perform certain functions in the application of the article and adapted to contain volatile material or substances, the fumes of which are useful for medicinal purposes.

20 The invention is illustratively exemplified in the accompanying drawings, in which, Figure 1 is an elevational view of my improved device and Figure 2 is a substantially longitudinal section of the same; and Figure 25 3 is a view of the several compartments of the inhaler in separated positions; and Figure 4 is an elevational view of the device showing the compartments arranged as they would appear when the device is used as a 30 neuralgic pencil.

Referring to the drawings, 10 designates a tubular body portion having a closed end 10^a provided with an outwardly projecting nipple 11. The end portion of the body 10, 35 extending inwardly from the closed end thereof is of a smaller diameter than the main body portion and is set off from the latter by an annular raised bead 12. A series of perforations 13 are provided in 40 the portion disposed between the bead 12 and the open end of the tube. The nipple 11 is exteriorly threaded and is adapted to receive the threaded bore of a mouth piece 14 which comprises a tubular member having 45 one closed end and a tapered open end and through the center of which is disposed an integral projection 14^a wherein is formed the threaded bore above referred to, as clearly illustrated in Figures 2 and 3.

50 The open end of the tubular body 10 receives a cap 15 which comprises a cup shaped member having a bead 16 encircling the midportion thereof and adapted to seat against the edge of the body 10. If desired 55 a menthol cone, designated 17, may be attached to the cap 15 and arranged so as to

project outwardly from the cap and into the body portion 10 closely adjacent the orifices 13. The diameter of the cap 15 is similar on both sides of the bead 16 and is substantially the same dimension as the smaller end of the body portion 10 so as to enable the cap to be inserted into the open or larger end of the body 10 in either axial position, i. e. with the menthol cone 17 disposed outside or inside of the body.

To facilitate the use of the article for a nasal inhaler the invention is provided with a nose piece 18 comprising a tubular member having a closed and an open end and of 70 a diameter to embrace the smaller diameter of the body 10, i. e. between the bead 12 and the closed end 10^a. The nose piece 18 is adapted to be slipped over the closed end of the body piece 10 and the edge thereof seated against the bead 12, as shown in Figures 1 and 2. The closed end of the nose piece 18 is provided with an outwardly projecting nipple 19 which is adapted to be inserted into the nostril of the user and which is provided with a bore aligned with the opening in the mouth piece 14 and nipple 11.

When it is desired to use the inhaler as a nasal instrument the compartments are arranged as shown in Figures 1 and 2, and the nipple 19 is inserted into the nostril of the user. By the act of inhaling, air is drawn through the orifices 13 and directed against the menthol cone 17, which will mix with 90 the air to form medicated fumes, whereupon the fumes thus formed will pass through the body 10, nipple 11 and outwardly through the nose piece and nipple 18 and discharge into the nostril.

If it is desired to employ the article as a mouth inhaler the nose piece 18 is removed and placed over the projecting end of the cap 15, as shown in dotted lines in Figure 2, and the shaped end of the mouth piece 14 is 100 inserted between the lips of the user, who may inhale fumes from the interior of the body 10, as above described.

By rearranging the compartments, as shown in Figure 4, the cap 15 may be reversed so as to bring the menthol cone 17 on the outside where it may be used as a neuralgic pencil.

Having now described my invention what I claim is:

1. An inhaler and pencil of the character described, comprising a perforated tubular

body portion closed at one end and provided with a bored nipple, a cap to close the opposite end of the tubular body portion and provided with a receptacle to hold medicine, 5 a mouth piece adjustable over said nipple, and a nose piece adapted to embrace the closed end of the body portion.

2. An inhaler and pencil, as claimed in claim 1, in which the body portion is provided with a bead to receive the edge of the nose piece, the diameter of the said body portion being smaller on the side of the bead having the closed end, and the cap is provided with a bead midway thereof to 10 abut the edge of the body portion in both possible reverse positions of the cap and to abut the edge of the said nose piece when the latter is placed thereover to expose the mouth piece, substantially as described.

3. In an inhaler and pencil of the character described, the combination with a perforated tubular body portion provided with a closed end having a threaded nipple with a through bore and a projecting annular bead disposed about the body and forwardly of the 20 perforations thereof, the portion of the body

between the said bead and the closed end being of a diameter smaller than the diameter of the body on the opposite side of the bead, of a cap to close the opposite end of the body portion and having a bead disposed midway of its length and adapted to abut the edge of the body portion in both possible axial positions of the cap in the body, the said cap being provided with a receptacle to hold medicine, the latter being adapted to project from one end thereof, a mouth piece having an outer shell closed at one end provided with a bored nipple adjustable over said nipple at the closed end of the body portion 25 and a shaped open end, and a nose piece capable of embracing the said cap or the closed end of the body portion, abutting the bead of the latter and extending over the mouth piece, the said nose piece being provided with a bored nipple at the closed end thereof axially aligned with two passages through the first nipple to the interior of the body.

In testimony whereof I affix my signature.

HERMAN DANZIGER.
